BY
E. T. Silvius,
ATTORNEY.

UNITED STATES PATENT OFFICE.

GEORGE W. HAHN, OF INDIANAPOLIS, INDIANA.

SPONGE HOLDER AND MOISTENER.

1,218,081.

Specification of Letters Patent.

Patented Mar. 6, 1917.

Application filed January 21, 1916. Serial No. 73,449.

To all whom it may concern:

Be it known that I, GEORGE W. HAHN, a citizen of the United States, residing at Indianapolis, in the county of Marion and State of Indiana, have invented a new and useful Sponge Holder and Moistener, of which the following is a specification, reference being had to the accompanying drawings, and to the letters and figures of reference marked thereon.

This invention relates to an appliance that is designed for holding and using a sponge or equivalent article whereby to wash dust or mud from automobile or other vehicle bodies, the invention having reference more particularly to a sponge-holder that is capable of conducting water from a water-hose to the sponge or other mop-like device.

An object of the invention is to provide a convenient handle for holding a piece of sponge or other article suitable for washing purposes, in order that the operator may wet the sponge and carry on the washing operations without wetting his hand, especially in the cold seasons when the operator may desire to wear a glove.

Another object is to provide an inexpensive and efficient sponge-holder that shall be so constructed as to be adapted to be connected to a water-hose and conduct water under pressure to the sponge in order that the sponge and the surface operated upon may be thoroughly wet at all times and not liable to cause scratching of varnished surfaces, and in order that the surfaces may be rinsed with flowing water immediately after having been washed, and without requiring the use of a separate instrument for rinsing operations.

A further object is to provide a sponge-holder and moistener that shall be so constructed as to permit of ready removal of a worn or soiled sponge and the application of a new one, and which holder shall be durable and economical in use.

With the above mentioned and other objects in view, the invention consists in a hollow frame constructed to constitute a handle and a core for the sponge adapted to conduct liquid from a water-hose to the sponge, the frame comprising also a yoke for connecting the sponge to the core, and means for securing the yoke to other portions of the frame; the invention consisting further in the novel parts, and combinations and arrangements of parts, as hereinafter particularly de-

scribed and further defined in the accompanying claims.

Referring to the drawings, Figure 1 is a perspective view of the sponge-holder and moistener having a sponge connected thereto; Fig. 2 is a sectional elevation approximately on the line A A on Fig. 1, omitting the sponge; Fig. 3 is a longitudinal central section of the holder and moistener and a sponge, partially broken away, connected thereto; Fig. 4 is an end view of the handle member of the holder; Fig. 5 is a fragmentary section of the handle member, as on the line B B on Fig. 1; Fig. 6 is a perspective view of the main part of the frame which forms a core for the sponge and conduit for moistening it; and, Fig. 7 is a fragmentary section approximately on the plane of the line B B, omitting the sponge.

Similar reference characters on the different figures of the drawings indicate corresponding elements or features of construction herein referred to.

The handle member may be composed of wood, vulcanized fiber or rubber, or other suitable substance turned so as to form a suitable handle portion 1, a cylindrical head portion 2, and a middle portion 3 that is less in diameter than the head portion, the head portion being less in diameter than the handle portion. The end of the handle portion preferably has a socket 4 therein, the end of the head portion 2 having a squared face 5. The handle member has a cylindrical bore 6 extending therethrough to receive a water-conducting tube. The exterior of the head 2 has two longitudinal grooves 7 and 8 therein extending from the face 5 a suitable distance, and from the grooves two sockets 9 and 10 extend respectively into the body of the head and they may suitably extend to the bore 6, the grooves being in opposite portions respectively of the head. The end face 5 of the head has two keyways 11 and 12 that extend from the bore 6 at right angles to the plane of the sockets.

A tube 13 is provided which is of suitable length to constitute a water-tight lining and conduit through the handle member and extend beyond the member to constitute the core for the sponge, the tube being inserted in the bore 6 and provided with a stop pin 14 that constitutes keys which are placed in the keyways 11 and 12 to retain the tube in the required position and prevent rotation thereof in the handle member, the tube extending

through the socket 4. A cap 15 is provided which has a boss 16 on its back that is inserted in the socket 4, the cap being secured to the adjacent end portion of the tube 13 and seated against the adjacent end of the handle member. The cap has a flange 17 thereon having screw-threads 18 therein and constituting a socket to receive a hose connection, a packing washer 19 being placed in the socket. Preferably the cap is screwed onto the tube 13 so as to firmly hold the different parts in place. The projecting core portion of the tube has a suitable number of small outlet apertures 20, 21, in the wall thereof and a plug 22 tightly secured in the end of the core to close the conduit.

For the purpose of holding a sponge securely for use a spring ring 23 is provided which is adapted to snugly embrace the exterior of the head portion 2, but when slipped back over the middle portion 3 will not pass over the handle portion 1. A yoke is formed of spring wire and comprises a crook or loop 24 from which two rods 25 and 26 extend, the crook being adapted to extend over the end of the core, the ends of the rods having inwardly extending lugs 27 and 28 thereon respectively to be inserted in the sockets 9 and 10 respectively when the rods are drawn into the adjacent grooves 7 and 8. The tension of the crook 24 is such as to cause the rods to extend divergently therefrom when released so that a piece of sponge 29 may be forced between the rods, the latter being afterward forcibly pressed against the sponge and drawn by the operator into the grooves 7 and 8 respectively after having forced the core into the body of the sponge, the rods being retained in place by means of the ring 23 which is forced over them.

In practical use the handle portion 1 is held in the hand of the operator who may use the sponge for various purposes, either dry or moistened, and may moisten or thoroughly saturate the sponge in a pail of water when no other source of water supply is convenient. When a water-hose is convenient its coupling member is connected with the screw-threads 18 of the socket on the end of the handle member, so that water is forced through the tube 13 and out of the apertures in the wall of the core of the sponge so as to saturate the sponge to any desired degree. The sponge is moved over the surface required to be cleansed until the dust or dirt is loosened, and while an ample supply of water is provided the sponge may be pressed repeatedly upon the surface so that the water shall flow freely therefrom and rinse the loosened dirt and float it away.

Having thus described the invention, what is claimed as new is—

1. An improved sponge-holder and moistener comprising a tube having apertures in its wall near one end of the tube, a plug secured in said end of the tube, a coupling device secured to the opposite end of the tube, a key pin secured in the wall of the tube intermediately of the ends thereof and extending from the wall, and a hollow handle on the tube between said key and said device and secured thereto, said plugged end of the tube being adapted to be forcibly inserted into the sponge. 75

2. An improved sponge-holder comprising a handle member having a handle portion and a cylindrical head portion that is less in diameter than the handle portion, the member having also a middle portion that is 80 less in diameter than the head portion, the head portion having two longitudinally-extending grooves in its exterior and also two sockets extending transversely from the grooves respectively and inwardly adjacent 85 to said middle portion; a yoke comprising an elastic crook and two rods having each a lug thereon, the rods extending in the grooves respectively, the lugs extending respectively into said sockets; and a spring 90 ring embracing the two rods and removable therefrom to said middle portion of the handle member.

3. In a sponge-holder and moistener, the combination of a hollow handle member having a transverse keyway in one end thereof, a tube extending through the handle member and also outward beyond said end, the wall of the tube beyond said member being apertured, a plug secured in the outer end 100 of said tube, a key pin secured in and extending transversely through the wall of said tube and seated in said keyway, and a coupling device secured to the opposite end of said tube and seated against the opposite end 105 of said member, with a yoke extending about the outer plugged end of said tube and connected to said handle member. 95

4. In a sponge-holder and moistener, the combination with a natural sponge, of a core 110 adapted to be forcibly inserted endwise into the sponge, a handle secured to the core, a yoke comprising an elastic crook and two rods extending from the crook to embrace and compress the sponge on the core, and 115 means for securing the rods to the handle.

In testimony whereof I affix my signature in presence of two witnesses.

GEORGE W. HAHN.
